BENDING DEVICE

Everett P. Taylor, Athens, Ga.

Application May 26, 1933, Serial No. 673,091

4 Claims. (Cl. 153—46)

This invention relates to a tube bending device and more particularly to a tube bending device adapted to be placed on the top of a table or support and lie in a most convenient position to receive the tube, and the bending operation performed with the least expenditure of time and energy.

Another object of the invention is to adapt the device to bending tubes on different curves and while so bending the tubes to hold them from slipping in the direction of the pressure by the bending lever.

Another object of the invention is to provide a rotatable bending wheel for making the bend on a lever so shaped as to secure the most advantageous leverage during the bending operation and to locate the wheel on the lever so that its pivot may be so held that it has no tendency to become inclined to the plane of the wheel.

Another object of the invention is to provide a holding jaw in proximity to the bending lever so that the jaw may be automatically released on restoring the lever to its normal position after a bending operation.

Another object of the invention is to arrange the parts so that the lever carrying the wheel and the holding jaw are all open to the top side of the device to permit the work to be laid in from the top on one side of the lever and the holding jaw.

With these and other objects in view which will now be developed as the description proceeds, I will describe my invention in connection with the accompanying drawing in which:—

Figure 1 is a view from above looking down on the bending lever, wheel and clamping jaw, the table or bench support for these parts being left off in this view.

Figure 2 is an elevation of the support and the bending device as in use while bending a tube and a vise which has legs passing through the bending device to hold it on a supporting bench or table.

1 is an ordinary bench or table having legs 2 and a top 3.

The tube bending device lays flat on the top 3 of the table, as shown in Figure 2, and comprises an upper plate 4 and a lower plate 5. These plates are held together near their edges by bolts 6, 7 and are spaced apart sufficiently to accommodate the end of a lever 8 having a pivot 9, which may comprise an ordinary bolt, passing through both the upper and lower plates. The end 8 of the lever may have a slot 10 rounded at either end and the pivot bolt 9 may slide in

the slot 10 and rest in either of the rounded end portions in the lever to lengthen or shorten the distance between the pivot bolt 9 and a roller wheel 12. It is further apparent that by removing the pivot bolt 9 the lever end 8 may be moved between the plates 4 and 5 to a position where the pivot bolt 9 may be inserted in a second hole 13 in the two plates. Thus the end of the lever 8 may have its pivot located in various positions, only two being shown in Figure 1, to secure bends in a tube of different diameters, or to first partially bend a tube on a larger diameter and then adjust the length of the lever part 8 to bend the tube on a smaller diameter or radius.

The lever 15 having the end 8 is conveniently bent at 16 for purposes hereafter described. The roller 12 is altogether on one side of the lever 15, there being provided a strip 17 suitably bent to extend over the roller and perforated to receive a bolt. By this construction, when the tube 20 to be bent is laid from the top downwardly to rest on a bracket or support 21 carrying a clamping jaw 22, the tube does not have to be inserted endways but may be inserted from above and rest on the bracket or support 21 and the top side 80 of the lever 8.

The bracket 21 carries the clamping jaw 22 on an eccentrically mounted pivot 25, whereby when the pivot is turned the jaw 22 may be moved back and forth to vary the angle between the lower edge of the jaw and clamped pipe or tube. I further provide a handle or operating rod 26 pivoted at 27 on the support 21 and adapted to have its back portion rest against the upper end of the clamping jaw 22 so that when the handle is moved in the direction of the arrow A, shown in Figure 1, the back of the handle will strike the end of the clamping jaw 22 and disconnect it from the tube 20. When the handle is moved in the direction of the arrow B the lower end 30 will come against the top of the clamping jaw 22 and press it into engagement with the tube 20.

In order to automatically release the clamping jaw 22 from the tube or rod 20 after a bending operation, the handle 15 is bent as shown at 16 and on its return from the bending operation it is brought in contact with the outer end of the handle 26 and if the handle has been pushed in the direction of the arrow B it will automatically move it back in the direction of the arrow A as the lever 15 is retracted from its bending operation. Furthermore, the handle 26 will then be brought against the upper end of the clamping jaw 22 and raise it from the tube or rod 20.

To get the best effect of the lever 15 and to save space it is bent at the point 16 and during the pulling down of the lever to bend the tube it is evident that the bend at 16 renders it more 5 convenient to the operator and furthermore locates the lever 15 so that it will automatically open the jaw 22 on being returned after the bending operation.

In order to bend a tube into a circle for example, I lessen the diameter of the quadrangular portion 4 at a location 35 and by changing the pivot 9 of the lever to shorten the end 8 thereof, I am able to give the tube an extra inward bend at the location 35 and by repeating 15 this operation at various places in the tube I can bend the tube into a circle instead of a quadrangle.

It is desirable frequently to screw-thread the end of the tube and I have provided a rise 40 20 having an upper portion 41 pivoted to the lower portion at 42 whereby the vise may be opened and the tube placed in the holding opening 43 to hold it during the screw-thread making operation. I conveniently pass the legs of the vise 25 down through the holes 45, 45' in the upper plate 4. This vise is in convenient position to receive the tube 20 and hold it while screw-threads are being formed on the ends of the tube.

Having now described one form of my invention, it is apparent that various modifications 30 thereof may be made which come within the terms of the following claims:—

1. A rod or tube bending device comprising a table support, upper and lower plates resting flatwise on the support and having between them 35 a bending lever, said lever having near its inner end a plurality of holes connected by a slot in the lever end, said lever extending beyond the plates and having a bend therein and at its bend 40 having a pivot bolt, a roller pivoted on the top side of said lever at said bend, a strip attached to one side of said lever and embracing said

bolt in the lower end to maintain the bolt at right angles to the plane of the lever and a work clamp having a releasing portion in the path of movement of said lever whereby a tube to be bent may be laid on said lever from above and the roller brought against the tube by operating the lever about its pivot. 80

2. A tube bending device comprising upper and lower plates, a lever pivoted between the plates, said lever being bent at a point beyond the plates 85 and having a grooved roller pivoted in said bend, a tube clamping and holding device having a handle in the path of the movement of said lever, said handle being pivoted on the tube holding device and constructed to release the holding device when contacted by said lever. 90

3. A tube bending and holding device comprising a lever having a grooved roller pivoted thereto, a tube clamping and holding mechanism including a handle in the path of the lever, said tube clamping and holding device having means to release the held tube when the bending lever is moved against said handle. 95

4. A tube or rod bending device comprising a table support, upper and lower plates extending 100 parallel to the top of the support and bolted thereto, a bending lever between the plates and extending beyond the same, said lever having a pivoted roller on the side of the lever and a strip attached to the lever at one end and embracing 105 the pivot of the roller, a pipe support having a clamping jaw on its upper side and a handle for operating the clamping jaw after a tube has been laid on the clamping jaw support and the lever, whereby a tube may be inserted from above 110 to rest on the bending lever and clamping jaw support and the clamping jaw operated by the handle to clamp the pipe and the lever carrying the roller operated to bend the tube, said handle being in the path of movement of said lever and 115 operated to release the clamp. 110
